UNITED STATES PATENT OFFICE.

BURDETTE FYE, OF REYNOLDSVILLE, PENNSYLVANIA.

FOLDING SUPPORT.

1,044,879.

Specification of Letters Patent. Patented Nov. 19, 1912.

Application filed May 25, 1912. Serial No. 699,663.

To all whom it may concern:

Be it known that I, BURDETTE FYE, a citizen of the United States of America, residing at Reynoldsville, in the county of

5 Jefferson and State of Pennsylvania, have invented certain new and useful Improvements in Folding Supports, of which the following is a specification, reference being had therein to the accompanying drawing.

10 This invention relates to foldable supports especially designed for tables, chairs and other furniture.

The primary object of my invention is to provide a corner bracket with a foldable leg 15 holder that can be locked in a rigid position relatively to the bracket, whereby a - table or other piece of furniture can be safely supported by legs connected to said holders.

20 Another object of this invention is to provide a corner bracket for furniture that permits of the support of a piece of furniture being folded, whereby it will occupy a comparatively small space in storage or 25 during transportation.

A further object of this invention is to accomplish the above results by a mechanical construction that is durable, easy to install and inexpensive to manufacture.

30 With the above and other objects in view, the invention resides in a novel construction, combination and arrangement of parts to be hereinafter specifically described and then claimed.

35 Reference will now be had to the drawing, wherein:—

Figure 1 is a perspective view of the foldable support. Fig. 2 is a side elevation of the same. Fig. 3 is a horizontal sectional view of the support, and Fig. 4 is a vertical sectional view of a portion of the same showing a leg attached thereto.

The reference numeral 1 denotes a corner or angle bracket that has side walls 2. This 45 bracket is adapted to be secured to the underneath side of the table top or other piece of furniture by screws or other fastening means that extends through openings 3 provided therefor in the top of the bracket. The underneath side of the bracket 1 is provided with depending apertured parallel lug 4 and pivotally mounted between said lug by a bolt 5 and a nut 6 is an apertured lug 7, carried by the upper 50 end of a rectangular support 8 that fits in

the angle of the walls 2 of the bracket. The lower end of the support 8 has a socket 9 to receive the stem 10 of a leg 11, said stem being retained within the socket by a set screw 12 or other fastening means.

60 The support 8, at the walls 2, is beveled, as at 13 and the beveled walls of said support are provided with sockets 14.

Formed integral with the inner sides of the walls 2 are longitudinal housings 15, 65 said housings having the inner ends beveled, as at 16 to engage the beveled walls of the support 8. The housings 15 have longitudinal bores 17 and longitudinal slots 18 in communication with said bores. The 70 outer ends of the bores 17 are closed by screw plugs 19 provided with longitudinal openings 20. Slidably mounted within the bores 17 are locking bolts 21 having stems 22 extending through the openings 20 of 75 the plugs 19. Encircling the stems 22, between the bolts 21 and the plugs 19 are coiled compression springs 23 that hold the bolts 21 in a normally extended position. Each of the bolts 21 has a hand piece 24 80 that extends through the slots 18 to permit of the bolts being retracted. The ends of the bolts 21 extend into the sockets 14 of the support 8 and lock said support in the angle of the walls 2.

85 With the bolts 21 withdrawn from the sockets 14, the support 8 and the leg 11 attached thereto can be swung inwardly, consequently the table provided with the foldable support will occupy a comparatively 90 small space with the leg thereof folded under the top of the table.

95 While in the drawing there is illustrated a preferred embodiment of my invention, it is to be understood that the structural elements are susceptible to such changes as fall within the scope of the appended claim.

What I claim is:—

A folding support comprising a bracket 100 including a pair of side arms integral with and disposed at right angles with respect to each other and further including a top plate integral with the top edges of said arms, a supporting member adapted to abut against said arms at the intersection thereof 105 and having a portion of the opposite corners thereof beveled, said support provided with sockets, means for pivotally connecting one corner of said support to the lower face of said top plate, housings carried by 110

the inner faces of said arms in proximity to their lower edges and having beveled ends engaging the beveled portions of said member when the latter is moved to engage said arms thereby preventing the shifting of said member, and spring pressed bolts slidably mounted in said housings and adapted to engage in said sockets for retaining the

supporting member in a vertical position between said arms.

10

In testimony whereof I affix my signature in the presence of two witnesses.

BURDETTE FYE.
